UNITED STATES PATENT OFFICE.

CHESTER B. WATTS, OF WINCHESTER, INDIANA, ASSIGNOR OF ONE-HALF
TO JOSEPH WATTS, OF WINCHESTER, INDIANA.

GRAVITY PLUMB-LEVEL AND INCLINOMETER.

No. 851,717.

Specification of Letters Patent.

Patented April 30, 1907.

Application filed December 3, 1906. Serial No. 346,059.

To all whom it may concern:

Be it known that I, CHESTER B. WATTS, a citizen of the United States, residing in the city of Winchester, in the county of Randolph and State of Indiana, have invented a new and useful Gravity Plumb-Level and Inclinometer, of which the following is a full, accurate, and lucid specification and exposition, being such as will enable others skilled in the art to which it appertains to make and use the same with absolute exactitude.

Broadly stated, my invention incorporates in a single tool a level, a plumb, and an inclinometer, and comprising in its construction a plurality of dials having graduations thereon and hands or pointers operating in connection with said dials with means for accurately actuating said hands or pointers by gravity, substantially as will be herein described in concrete detail and as shown in the accompanying drawings.

The object of my present invention is to provide a gravity plumb or level and inclinometer of simple and inexpensive construction, which will be positive in action, strong and durable in construction, neat and mechanical in appearance, and by the employment of which may be determined any degree of inclination, as well as the vertical or horizontal status, of any object to which it may be applied.

Probably the best exemplification of the possibilities and advantages of my invention are shown most clearly in the accompanying drawings, in which—

Figure 1 is an upper edge view of my invention, showing a portion of the body in which the invention is attached; Fig. 2 is a side elevation of the same; Fig. 3 is an enlarged central cross section, as taken on the line X—X of Fig. 2; Fig. 4 is a diagrammatical view of the dials and the graduated band; Fig. 5 is a central section as taken on the line Z—Z of Fig. 1; Fig. 6 is a side elevation of the revoluble disk; and Fig. 7 is a perspective view of the weight.

Similar indices denote like parts throughout the several views of the drawings.

In order to render the construction and operation of my invention still more facile I will now take up a detail description thereof, in which I will set forth the construction and uses of the invention as briefly and as compactly as I may.

Figs. 3, 4, 5, 6 and 7 are made on a scale 55 which may be termed actual size while Figs. 1 and 2 are on a reduced scale.

Referring now to the drawings in detail the numeral 1 denotes the body which may be of any suitable length or material, and ordinarily it may be a bar, usually of wood, of any preferred size.

Centrally of the body 1 a notch is cut from the upper edge down into and across the body to receive the mechanism which I will now 65 describe.

Referring now to the invention proper: The numerals 2 and 3 denote the end members of the mechanism case; the numerals 4 and 5 denote the sides thereof, and the 70 numeral 6 denotes the top of the same. The sides and ends are secured together by screws or the like forming a box-like receptacle which may be secured to and covered by the top 6, said receptacle being closed at 75 the bottom by the bottom of the recess or notch in the body. The width of the top 6 is such as to project out beyond the sides, and in length such as to project a considerable distance, comparatively, beyond the 80 ends, the former being shown in Fig. 3, and the latter in Fig. 5. Said projections being for purposes which will presently appear.

The top 6 is let in flush with the face of the body 1 where it is secured by the screws 85 a and b. In the center of the top 6 is a square, inwardly converging, aperture 6' which is covered or closed by the glass-sight 7 secured to the underside of the top 6, as shown in Figs. 3 and 5. 90

The sides 4—5 and the ends 2—3 are of a depth such as to rest on the bottom of the said notch in the body 1, when the top 6 is in position as specified. Formed through the sides 4 and 5 are circular apertures 4' and 5', 95 respectively. To the backs or inner faces of the sides 4 and 5 are secured the respective dials 8 and 9 which close said respective apertures 4' and 5', each having a circular graduated scale thereon, indicated by the numerals 10 and 11, respectively, and each being divided into groups indicated by numerals ranging progressively in both directions from "0", at the central upper part, to "180", at the lower central part of said dials. Formed through the center of each of said dials are the respective apertures 8' and 9', for the purposes presently appearing. 100 105

Of same size and covering the faces of the sides 4 and 5 are the respective crystals 12 and 13 which cover their respective dials but are spaced therefrom by the said sides as is shown in Fig. 3.

The numerals 14 and 15 denote face-plates contacting, at their upper edges, with the outer edges of the top 6, being of same length as the top 6, and extending down below the sides 4 and 5 to obtain a lateral bearing against the body, and being let in flush with the sides of the body 1, all substantially as shown in Fig. 3. Formed through the face-plates are the respective outwardly flaring circular apertures 14' and 15' which correspond with the respective apertures 4' and 5', as in Fig. 3. The faces of said plates 14 and 15 are flush with the respective sides of the body 1, as indicated in Fig. 1, where they 20 may be secured by a plurality of screws or the like as, for instance, the screws *c, d, e, and f*, in Fig. 2.

Secured to the backs of the dials 8 and 9, around the central apertures 8' and 9', are 25 the bosses 16 and 17 respectively, through which passes the shaft 18. Said shaft protrudes outward at each end slightly beyond the faces of the dials to receive thereon the hands, or indicators, 19 and 20.

30 Securely mounted on the shaft 18, between the bosses 16 and 17, is the comparatively large two-part disk composed of the members A and B, which members may be secured together in any preferred manner. Said disk should be composed of wood or 35 other light material.

The letter C denotes a weight formed preferably of lead or other heavy material. The center part of said weight extends out flush 40 and corresponding with the periphery of the disk, between the members of which it is contained, there being lugs extending out integral with and from each side of the weight which lugs pass through apertures 45 thereof formed through the side of each of the members A and B, as is indicated in the drawings, whereby when the weight is positioned and the members of the disk are secured together the weight will be locked 50 against removal in any direction as shown.

Secured around the periphery of the disk is a band or endless strip D, containing thereon a series gradations indicated by numerals from "0" to "180", being indicated 55 progressively in both directions from "0", which is directly opposite the center of the weight C, to "180" which is directly over the center of the weight C. Said band or strip D is so located that the gradations and 60 figures thereon may be observed through the glass 7, there being an indicating or centering mark 7' cut into or otherwise made across the glass 7 to indicate its center.

When constructed as set forth the arrangement of said parts are such that when the

under edge of the body 1 is resting on a level surface the weight C will, obviously, retain the disk normally in the position shown in Figs. 3, 5 and 6, with the indication mark "0" on the band D directly and centrally 70 under the line 7', that is to say,—centrally of the glass sight 7. At same time the hands 19 and 20 will be pointing directly upward, that is to the "0" on the respective dials 8 and 9. Now, for instance, if one end of the body 1 be raised up it is apparent that the weight C will by gravity prevent the disk from turning, but will adjust the disk by gravity whereby the hands 19 and 20 will continue to point directly upward, and as 80 the dials have been turned by the raising of one end of the body it will be seen that the hands will assume new points on the dials thereby indicating new gradations on the dials, and at the same time a new number 85 will appear under the line 7', and the new graduating marks indicated by the hands and below the line 7' will indicate the inclination assumed by the body 1.

It is also apparent that if the body is 90 placed in a vertical position the indicators will register at "90", while if the body be turned entirely over to the horizontal then they will indicate "180", and it is also manifest that any degree of inclination may be determined, at the points, between the two extremes.

I have herein described the best exemplification of my invention to me known at this time but I desire that it be understood that 100 various changes and variations may be made in the details thereof without departing from the spirit or sacrificing the advantages of my invention.

Having now given a complete exposition of 105 my invention, what I claim and desire to secure by Letters Patent of the United States, is—

1. In a gravity plumb-level and inclinometer, a body having a transverse recess 110 formed entirely therethrough, a boxing having side and end walls seated within said recess, said side walls being provided with apertures and being set in from the sides of the body, an apertured top plate overlying said 115 boxing and having its ends extended beyond the end walls thereof, securing means passing through such extended ends into said body, apertured face plates flush with the sides of the body and having their upper portions 120 bearing laterally against the side edges of the top plate and their lower portions extended below the boxing and bearing laterally against the body, means for securing said face plates in place, and glasses mounted in 125 conjunction with the several apertures; in combination with a pair of dials mounted in conjunction with the apertures of the side walls of the boxing, a peripherally-graduated weighted disk suspended rotatively be- 130

tween said dials, and indicating arms carried by the axis of said disk without the dials.

2. In a gravity plumb-level and inclinometer, the combination with an inclosing support, of a disk member supported rotatively therein on a horizontal axis and comprising a pair of laterally contacting disks each provided with an eccentric recess, a single weight received within both said recesses and locked between the disks against removal in any direction, and indicating means associated with said disk member.

3. In a gravity plumb-level and inclinometer, the combination with an inclosing support having observation openings in its side and top, of a disk member supported ro-

tatively therein on a horizontal axis and comprising a pair of laterally contacting disks, a weight having laterally projecting lugs, said disks being provided eccentrically with communicating recesses conforming to and receiving said weight, a graduated band mounted peripherally on both disks, and an indicating arm carried by the axis of the disk member.

In testimony whereof I have hereunto signed my name to this specification in the presence of two subscribing witnesses.

CHESTER B. WATTS.
